UNITED STATES PATENT OFFICE.

WILLIAM RAEURN, OF WATERBURY, CONNECTICUT, ASSIGNOR TO M. E. BERNHARDT COMPANY, INC., OF NEW YORK, N. Y., A CORPORATION OF NEW YORK.

DESIGN FOR A POCKET LIGHTER.

Application filed September 2, 1927. Serial No. 23,282. Term of patent 14 years.

To all whom it may concern:

Be it known that I, WILLIAM RAEURN, a citizen of the United States of America, residing at Waterbury, in the county of New Haven and State of Connecticut, have invented a new, original, and ornamental Design for Pocket Lighters, of which the following is a specification, reference being had to the accompanying drawing, forming part thereof.

Fig. 1 is a perspective view of a pocket lighter showing my new design, and

Fig. 2 is an end elevation looking towards the right in Fig. 1.

I claim:

The ornamental design for a pocket lighter substantially as shown.

WILLIAM RAEURN.
